UNITED STATES PATENT OFFICE.

GEORGE MARSHALL FRENCH, OF CHICAGO, ILLINOIS.

BOAT-HULL CONSTRUCTION.

Application filed April 27, 1922. Serial No. 556,996.

To all whom it may concern:

Be it known that I, GEORGE M. FRENCH, a citizen of the United States, residing at Chicago, in the county of Cook and State of Illinois, have invented a new and useful Boat-Hull Construction, of which the following is a specification.

The invention pertains in its broadest aspects to an improved construction for the hull of a boat or vessel irrespective of size and use, but has particular reference to vessels of the smaller class such, for example, as pleasure boats.

The general aim of the invention is to produce a boat hull construction which is of a highly practical character, because it enables the hull to be made of exceptionally light weight and yet of ample strength and rigidity, and is capable of rapid and relatively easy construction due to its simplicity.

The invention involves the use of metallic plates to form the shell, and in the case of smaller vessels, such as motor boats, a non-ferrous metal is employed in order to counteract the injurious effect which such natural elements as the teredo worm, barnacles, corrosion, electrolysis, etc., have upon wood and ferrous metals. Further, my construction embodies a combined reinforcing and shell plate, flanged to impart thereto the desired strengthening quality. The flanges, however, are interrupted at regular intervals, preferably corresponding to the spacing of the transverse frame members or ribs so as to receive the latter. By this construction, the hull is rendered substantially rigid when completed, but the plates are made sufficiently flexible to permit them to be bent and flared into the form desired, thus facilitating their application to the frame. Moreover, the interruption in the flanges eliminates the water pockets formed by the continuous flanges of prior constructions.

In the accompanying drawings I have shown my invention as embodied in a hull constructed partially of metal and also in a hull constructed wholly of metal. Figs. 1 and 2 are fragmentary vertical sectional views through a hull taken respectively near the forward portion of the vessel and the rear portion of the vessel, and showing the upper portion of the hull with a wood planking. Fig. 3 is a view similar to Fig. 2 but showing the all metal construction. Fig. 4 is a fragmentary perspective view of

a small section of the hull. Fig. 5 is an inner side elevation of the same. Fig. 6 is a fragmentary plan view of a blank from which the reinforcing shell plate is formed. Fig. 7 is a fragmentary side view somewhat diagrammatic in character of the hull. Fig. 8 is an edge elevation of a section of the reinforcing shell plate showing in broken lines how the interruption of the flanges facilitates the bending at the point adjacent the transverse frame members.

While the invention is set forth herein-after with considerable particularity, I contemplate that various changes in the form, construction and arrangement of the parts may be made by those skilled in the art without departing from the spirit and scope of the invention as expressed in the appended claims.

The hull comprises essentially reinforcing shell plates 10 having turned reinforcing strips or members in the form of flanges extending longitudinally thereof with interruptions at frequent intervals to render the plates flexible. In combination with the plates 10, I employ plain sheets or strips 11, the opposite edges of which overlap the flanged edges of the plates 10 and are secured thereto in any suitable manner, as for example, by rivets 12. As shown in Figs. 4 and 5, the plate 10 is provided along both longitudinal edges with flanges 13, interrupted at regularly spaced intervals as at 14, such intervals being spaced in accordance with the spacing of the transverse frame members 15 of the hull. As shown in Fig. 6, the plates 10 are formed from a blank 10^a having its edges notched as at 14^a to provide wing portions 13^a to be bent at right angles to form the flanges 13 interrupted at 14. These plates may be drilled to provide holes for the rivets 12.

Preferably the reinforcing shell plates 10 are made with straight edges in order to facilitate the shaping operation producing the flanges 13, and because of the fact that the hull is of greater dimensions in its central and rear portions than in its forward end, it is necessary for the plates to increase gradually in width from their front ends rearwardly as shown in Fig. 7. Moreover, it is necessary for these plates 10 to curve from front to rear, as a whole. In order, therefore, to obtain the straight flanged edges, these plates are made from a plurality of sections joined together end to end,

as shown in said Fig. 7. The plain overlapping plates 11 on the other hand may have curved edges and may be made of any length practicable.

5 It may be observed that because of the interrupted character of the flanges, notches are provided therein for receiving the transverse frame members 15, to which the plates are secured directly as by riveting. The 10 members 15 are also preferably made of sheet metal, but of a relatively heavy gauge, and are bent along one longitudinal edge to form a stiffening flange 15a. The notches 14 perform a three-fold function. They render 15 the plate flexible permitting it to be flared readily and also to be bent longitudinally as illustrated clearly in Fig. 8, the bend occurring at the frame members; they enable 20 the sheets to be secured together flat upon the frame members; and they provide passageways upon the inner side of the shell permitting the escape of water from the upper sides of the flanges, it being apparent that 25 such flanges if continuous would form pockets for collecting water. It will also be apparent that the stiffening members or flanges 13 are entirely free and that their sole function is to reinforce the shell plates longitudinally 30 thereof.

30 Referring to Fig. 3, it will be seen that my invention is capable of use where the shell of the hull is constructed entirely of sheet metal plates. As shown in this figure, the 35 flanged reinforcing shell plates 10, and the plain sheets or plates 11 alternate from the upper edges of the hull to the keel 16, the plates between the bottom and side walls of the shell being bent or curved transversely. 40 17 designates the floor of the vessel which may be of any suitable construction.

40 In Figs. 1 and 2 I have illustrated how my invention may be embodied in a hull constructed of metal in its lower portion with wood planking above the water line. 45 In this instance I have provided a special connection between the uppermost plate 10 and the wood planking 18. Such connection may consist of a pair of plates 19 and 20 the former overlapping at its lower edge the uppermost plate 10 and having an inturned 50 flange 21 at its upper edge which is secured to a similar flange 22 at the lower edge of the plate 20. The upper edge of the latter plate is preferably inserted between the wood 55 planking 18 and the frame members 15, and is suitably secured to the latter. Herein I have shown brackets 23 in substantially inverted U-form for this purpose. Preferably the plates 19 and 20 are spaced from the frame members 15 by shims 24 and 25. The lower edges of the wooden planking may be 60 protected by an angular strip 26. The wooden planking as shown is what is known as the double skin construction. A comparison of Figs. 2 and 3 will show that I

employ the U-shape bracket 23 only in the forward portion of the vessel where the radius of curvature between the bottom and upright portions of the shell is substantially greater.

70 It may be observed that I have produced a hull construction which is of a highly advantageous character and which is capable of wide application. I believe that I am the first to have produced a combined reinforcing and shell plate which is flanged to 75 impart the necessary rigidity to the hull when secured to the frame members and yet is capable of flaring and bending to accommodate itself to the shape of the hull at 80 any point therein. By the use of this reinforcing shell plate, in combination with the plain sheet or plate, these plates being employed alternately and secured directly to the transverse frame members, a construction 85 of exceeding simplicity and hence of extremely low cost is evolved. The metal necessary to be employed to impart the necessary rigidity is reduced to a minimum, so that the cost of construction, and the weight of 90 the completed hull, are correspondingly reduced. It may be noted that the flanged plates render it possible to eliminate the usual longitudinal stringers. The absence 95 of water pockets upon the inner sides of the shell is also believed to be of substantial importance.

I claim as my invention:

1. A boat hull having, in combination, a shell comprising plates having flanges at 100 their opposite longitudinal edges, other plates having plain edges overlapping the flanged edges of the first mentioned plates, and metallic frame members arranged in spaced relation and formed of sheet metal and flanged along one edge, said plates being secured directly to said frame members, and the flanges of the first mentioned plates being cut away to receive the frame members.

105 2. A boat hull having, in combination with transverse frame members, a shell comprising plates having flanges at both longitudinal edges, and other plates having plain edges overlapping the flanged edges of the first mentioned plates and rigidly secured thereto, said flanges being interrupted at regular intervals to receive the frame members.

110 3. A boat hull having transverse frame members spaced apart longitudinally, said members being made of sheet metal provided with a transversely extending stiffening flange, and shell plates secured flat upon said frame members in overlapping relation, certain of said shell plates having inwardly 115 projecting stiffening flanges extending longitudinally thereof between the frame members.

120 4. A boat hull having a shell made from plates having flanges at both longitudinal 125

- edges and plates having plain edges overlapping the flanged edges of the first mentioned plates and rigidly secured thereto, the flanged plates being formed in relatively 5 short sections having straight edges, and the plain plates being formed with curved edges, said sections being secured together in angular relation so as to produce a curvature for the flanged plates generally 10 connecting to that of the plain plates.
5. A shell construction for boats and the like comprising a plurality of shell plates formed of sheet metal, the alternate shell plates having inturned reinforcing flanges, 15 and a frame to which the shell is secured including transverse members also formed of sheet metal bent into angular form and having said shell plates secured directly thereto so that their inner faces lie flat 20 against said members.
6. A boat hull comprising a frame including transverse frame members and a shell comprising in its lower portion a plurality of sheet metal plates secured together 25 in overlapping relation and to said transverse frame members, and a wooden planking secured to the frame members above the sheet metal plates and forming the upper portion of the shell, and means for connect-
- ing the uppermost shell plate to the wooden 30 planking, certain of said metallic plates providing longitudinally extending reinforcement members for the hull.
7. In a boat hull, the combination with a frame including a transverse frame member 35 and a wooden planking secured to the frame members in the upper portion of the vessel, of a metallic bottom construction for the vessel including a plurality of plates secured directly to the frame members, and a pair of 40 connecting plates secured respectively to the metallic shell construction and the wooden planking and at their adjacent edges having inturned flanges secured together.
8. In a hull, the combination of a metallic 45 shell construction and a wooden planking, a frame to which said shell and planking are secured, and means for securing the uppermost plate of the shell construction to the frame including a metallic bracket secured 50 upon the inner side of said plate below its upper edge, the upper edge of said plate terminating between the planking and the frame.

In testimony whereof, I have hereunto 55 affixed my signature.

GEORGE MARSHALL FRENCH.
